United States Patent Office

Des. 210,659
Patented Apr. 2, 1968

210,659

CHAIR

David D. Granger, Conover, N.C., assignor to Maxwell Royal Chair Co., Hickory, N.C., a corporation of North Carolina

Filed May 15, 1967, Ser. No. 7,115

Term of patent 14 years

(Cl. D15—1)

I claim:

The ornamental design for a chair, as shown.
